UNITED STATES PATENT OFFICE

2,502,298

COMBINED FUNNEL AND INVERTED DISCHARGING BOTTLE THEREABOVE, WITH MEANS TO STOP FLOW INTO FUNNEL

William Rufus White, Nashville, Tenn.

Application February 21, 1946, Serial No. 649,293

3 Claims. (Cl. 226—19)

1

There is disclosed in the following specification and the drawings accompanying the same and forming a part of this application for patent, an invention the primary purpose of which is to provide an automatic device for filtering liquids.

This invention has for another object to provide means whereby a filter funnel cannot overflow during the filtering operation.

Another object of the invention is to provide means whereby liquid being filtered cannot evaporate during the filtering period though it may be a long one.

A still further object of the invention is to provide a filter stand provided with slidable closures for a funnel used in the filtering operation.

Other features and advantages will become more readily apparent from the following description and the accompanying illustrative drawings in which:

Figure 1 is a vertical sectional view of the invention,

Figure 2 is a top plan view of a stand, and

Figure 3 is a sectional view taken on line 3—3 of Figure 1.

While one embodiment of the invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of the device which is to be limited only in accordance with the appended claims. And while there is stated the primary field of utility of the invention it remains obvious that it may be employed in any other capacity wherein it may be found applicable.

In the accompanying drawings, and in the following specification, the same reference characters are used to designate the same parts and elements throughout and in which 10 refers to the complete invention which consists of a stand 11, the top 12 of which is provided with a bore 13 to receive the neck 14 of a bottle 15 adapted to be invertedly seated upon the stand. The legs 16, 17, 18 and 19 of the stand are of an exact length to permit a bottle 20, with a funnel 21 of a prescribed size to seat under the stand with the said bottle neck 14 depending about one-third way down into the body of the said funnel. The bottle 20 is to be equally as large as bottle 15 if not larger but should be no smaller than the latter.

2

Connecting legs 16 and 18 and 17 and 19 respectively are horizontal, runners 21' and 22 so positioned that the glass or plastic plates 23 and 24, slidable thereon will seat flush upon the upper edge 25 of the funnel in order to completely close the mouth thereof surrounding the neck 14 when the semi-circular recesses 26 and 27 are completely closed in around the neck 14 of bottle 15 and the inner edges 28 and 29 of said plates contact one another. The funnel 21 is, of course, provided with the usual filter disk 30.

In using the above described automatic filtering device, the bottle 20 with its funnel 21 is seated in position under the aperture 13 in the table top 12, then the bottle 15 is inverted and seated with said neck through the bore, then the plates 23 and 24 closed in upon said neck. The contents 31 of the bottle 15 will pour into the funnel 21 until the liquid reaches the edge 32 of the bottle neck, whereupon the same is sealed against entrance of air and the said contents will stop flowing down until after the contents 33 of the funnel filter out into bottle 20 to such an extent as to unseal said bottle neck 14 permitting contents from the bottle 15 to again flow into the funnel, which operation continues automatically until all of the contents of bottle 15 have been filtered into bottle 20. Bottle 20 being of a size to hold all of the contents of bottle 15, there can be no overflowing of the liquid. It is of course to be understood that the stand 11 may be of any length to hold any number of bottles and that the latter may be of any size from vials to demijohns or carboys, all depending upon the liquid to be filtered and the quantity thereof.

From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the pur-

view of the invention claimed may be resorted to, in actual practice, if desired.

Having thus described the invention that those versed in its particular art will fully understand how to make and use the same, as well as its functions, and without having attempted to detail all of the forms in which it may be made, all of its advantages, or all of the uses to which it may be put, it is declared that which is claimed as new and sought to be protected by Letters Patent is:

1. In a filtering apparatus, an elevated stand having an aperture in its upper portion, a liquid container having a neck received in said aperture, a second liquid container having a neck spaced beneath the neck of said first-mentioned container, a funnel carried by the neck of said second container and loosely receiving the neck of said first container, and means for closing an opening encircling said first-mentioned neck at the top of said funnel.

2. The combination of claim 1, wherein said means includes guides carried by said stand, and plates slidably mounted in said guides, said plates having opposing notched portions for embracing the periphery of the neck of said first container.

3. In a filtering apparatus, a substantially rectangular table top having an aperture in its upper portion, a liquid container having a neck

received in said aperture, legs carried by said table top supporting the same in an elevated position, a second liquid container having a neck spaced beneath the neck of said first container, a funnel carried by the neck of said second container, said funnel having a mouth portion loosely receiving the neck of said first container, guide members carried by said table top, and plates slidably mounted in said guide members toward opposite sides of the neck of said first container, said plates provided with opposing notches receiving opposite sides of the neck of said first container for closing an opening between the funnel and said first-mentioned neck.
